UNITED STATES PATENT OFFICE.

GORDON BRYAN, OF NEW YORK, N. Y., ASSIGNOR OF ONE-HALF TO BENJAMIN F. WATKINS, OF BRYN MAWR, PENNSYLVANIA.

HOE.

1,183,851.

Specification of Letters Patent. Patented May 23, 1916.

Application filed June 19, 1915. Serial No. 35,025.

To all whom it may concern:

Be it known that I, GORDON BRYAN, a citizen of the United States of America, residing in the borough of Manhattan, city, 5 county, and State of New York, have invented a certain new and useful Improved Hoe, of which the following is a specification.

This invention relates to hoes, particularly 10 to that class made of sheet metal. The object of the invention is to produce an article of this character that will be strong, durable, capable of resisting strains of rough usage and inexpensive to construct. The 15 salient features of the invention are exemplified by reference to the accompanying drawings, in which—

Figure 1 is a central vertical section of 20 a hoe head embodying the essential features of my invention and showing a handle applied thereto. Fig. 2, a face view of the socket member. Fig. 3, a face view of the flat blade; and Fig. 4, a sectional view of parts of the blade and socket member, taken 25 at right angle to the blade on line 4, 4, Fig. 1.

The blade 5 is formed from a right angular sheet of metal, as steel having hardening characteristics such as is commonly used for this purpose. At the upper central edge a 30 circular opening or recess 6, which may be about one-half of a circle, is formed. Extending downwardly from such circular recess the metal of the blade is embossed, corrugated or otherwise raised toward the face 35 of the blade by suitable pressure means, such as stamping dies, and the metal which originally occupied the space within the part circle that forms the contour of the central recess 6 is forced or pressed into a projecting 40 flange 7 surrounding said recess, the axis of said flange being at an angle to the plane of the blade. The raised or corrugated portion of the blade beneath the central circular opening partakes somewhat of the form of 45 a pear shaped embossment 8, the narrow or neck part 9 of which extends some distance down into or along the central part of the blade. This embossment and the formation of the flange 7 that extends from the central 50 recess, formed in or on the enlarged part

of the pear shaped embossment, imparts strength and rigidity to the blade without being raised or forced beyond the plane of the blade to an extent that would disrupt or weaken the metal when the blade is made of 55 a suitable steel having the requisite hardness to meet the rough usage to which the hoe is to be submitted. This part of the blade is re-inforced as hereafter described.

Sheet steel hoe blades should have a com- 60 paratively high percentage of carbon to afford the necessary hardness and wear-resisting qualities. It has been found that when the body of the blade is disturbed to any considerable degree, by embossing, corrugating or otherwise forming it the metal may be weakened to such an extent that the blade is liable to be disrupted by use although such weakening of the metal may not be apparent on inspection of the blade 65 after formation. To meet this difficulty, this invention provides that the other part or socket member of the hoe is also made of sheet steel, and as the sheet blank therefor has to be considerably distorted in forming 70 it into the desired shape a decarbonized or soft steel is used for this purpose. The socket 10 of this member is made cylindrical in form, or preferably conical as shown in Figs. 1 and 2, the seat in which the handle 75 11 is to be inserted being open at both ends. If of conical form the large end of the socket is at the front end of the seat, so that the handle, which is correspondingly tapered and passed into the seat from the front of 80 the blade, is securely held therein to resist dragging strains. The socket has a single lap seam 12 at its upper side. Pins 13 may be inserted through the handle and socket to securely hold the parts together. The 85 socket member has at its front end a downwardly extending plate 14 arranged at an angle to the axis of the socket and raised or corrugated at its central part, thus forming an embossment 15 adapted to fit in the embossment 8, 9 of the blade. The boundary portion of the plate 14 constitutes a flat flange 16 surrounding the embossment 15 and extending therefrom a considerable distance in all directions; this flange seats 90 100

against the front of the blade 5 when the parts are assembled, affording large flat contact surfaces. The flange 7 of the circular recess 6 then snugly embraces the under side 5 of the socket 10, extending half way around the socket in an angular direction relative to the socket's axis.

An examination of the two parts of the hoe, made as described and shown at Figs. 10 2 and 3, indicates that there are no weak points or parts that are liable to derangement and that when they are assembled as shown at Fig. 1 and adequately secured together, each part reinforces the other, thus 15 producing an article of finished appearance and of maximum strength for the amount of metal used in its structure. It will be observed that the juncture of socket 10 and plate 14 is an unbroken continuous bend 20 whose plane is at an angle to the socket's axis and includes one-half the circumference of the socket. In other words, this plane lies in a semi-ellipse whose minor radius equals that of the outside dimension of the 25 large end of the socket and the major radius equals the angular distance between the central part of the juncture and the center of the socket at its large end.

The blade and socket member may be fastened together by any suitable means, the 30 preferred connecting means being by the welding process known as spot-welding, as indicated by the marks 17. The locations for such welding may be selected at pleasure, 35 as for instance, the spots indicated in Figs. 2 and 3. The edges of the socket 10 which form the lap seam 12 may also be secured together by spot-welding.

I claim:

40 1. A hoe comprising a flat blade having an embossment extending centrally from its upper edge down into the body of the blade and a circular recess at the upper part of the embossment, a socket member formed of sheet metal with the socket closed by a single seam, open at both ends and having a downwardly extending plate at its front end embossed or corrugated to fit the embossment of the blade and a flat flange surrounding its 45 embossment adapted to seat snugly against the blade, the under side of the socket adjacent the embossed plate being seated closely into the circular opening at the upper edge of the blade, and means for securing the 50 two parts together by connecting the flat flange of the socket member to the blade.

2. A hoe comprising a flat blade having an embossment extending centrally from its upper edge down into the body of the blade and a circular recess at the upper part of the embossment with a flange around it extending angularly from the face of the blade, a 60 socket member formed of sheet metal with the socket closed by a single seam open at both ends and having a downwardly extend-

ing plate at its front end, embossed or corrugated to fit into the embossment of the blade at the front thereof, and a flat flange surrounding its embossment adapted to seat snugly against the blade, the under side of the 65 socket adjacent the embossed plate being seated fully and closely into the circular flange of the opening at the upper edge of the blade, and said parts being secured together at the flat flange of the socket member and 70 blade and at the circular flange of the blade and socket.

3. A hoe comprising a flat blade having an embossment extending centrally from its upper edge down into the body of the blade 80 and a circular recess at the upper part of the embossment, a socket member formed of sheet metal with the socket open at both ends tapered from the front end and a lap seam at its upper part and having a downwardly 85 extending plate at its front end embossed or corrugated to fit the embossment of the blade and a flat flange surrounding its embossment adapted to seat snugly against the blade, the under side of the socket adjacent 90 the embossed plate being seated fully and closely into the circular opening at the upper edge of the blade, the two parts being fastened together and the seam of the socket secured by spot-welding. 95

4. A hoe comprising a flat blade of sheet steel possessing hardened character and having an embossment extending centrally from its upper edge down into the body of the blade and a circular recess at the upper 100 part of the embossment, a socket member formed of soft sheet metal, as decarbonized steel, having a downwardly extending plate at its front end angularly arranged relatively to the socket's axis and embossed or 105 corrugated to fit into the embossment of the blade and a flat flange surrounding its embossment adapted to seat snugly against the blade, the under side of the socket adjacent the embossed plate being seated fully and 110 closely into the circular opening at the upper edge of the blade and means for securing the two parts together by connecting the flat flange of the socket member to the blade. 115

5. In a hoe a socket member formed of sheet metal and having a plate integral therewith embossed at its central part and extending from the end of the socket at an angle to the socket's axis, in combination with a blade member having a raised or embossed portion extending from one edge into the body of the blade adapted to fit over the embossment of the socket and a circular opening in the outer part of the embossed portion adapted to fit the juncture of the socket and 120 its connected plate. 125

6. In a hoe a socket member formed of sheet metal and having a plate integral therewith embossed at its central part and extending from the end of the socket at an angle to the 130

socket's axis, in combination with a blade member having a raised or embossed portion extending from one edge into the body of the blade adapted to fit over the embossment of the socket, a circular opening in the outer part of the embossed portion and a flange extending from the circular opening at an angle to the face of the blade and adapted

to fit the juncture of the socket and its connected plate.

In testimony whereof, I have hereunto
subscribed my name.

GORDON BRYAN.
